UNITED STATES PATENT OFFICE.

BERNARD D'ESCAVRAC, OF NEW YORK, N. Y., ASSIGNOR TO GUERLAIN PERFUMERY CORPORATION OF NEW YORK, OF NEW YORK, N. Y., A CORPORATION OF NEW YORK.

DESIGN FOR A PERFUME BOTTLE.

Application filed June 30, 1927. Serial No. 22,612. Term of patent 14 years.

To all whom it may concern:

Be it known that BERNARD D'ESCAVRAC, a citizen of the Republic of France, now residing at No. 33 West 55th Street, borough of Manhattan, city, county, and State of New York, has invented a new and original Design for a Perfume Bottle, of which the following is a specification, reference being had to the accompanying drawings, forming part thereof.

Figure 1 is a front view of the perfume bottle showing my new design, Figure 2 is an edge view of said perfume bottle, and Figure 3, is a plan view, of the perfume bottle showing my new design.

I claim:

The ornamental design for a perfume bottle as shown.

In testimony whereof, I have hereunto affixed my hand this 28th day of June, 1927.

BERNARD D'ESCAVRAC.
